LATCH

Chester O. Goserud, St. Paul, Minn.

Application May 19, 1950, Serial No. 10,049

Term of patent 14 years

(Cl. D50—5)

To all whom it may concern:

Be it known that I, Chester O. Goserud, a citizen of the United States, residing at St. Paul, county of Ramsey and State of Minnesota, have invented a new, original, and ornamental Design for a Latch, of which the following is a specification, reference being had to the accompanying drawing, forming a part thereof.

In the drawing:

Fig. 1 is a perspective view of the latch showing my design viewed from one side thereof.

Fig. 2 is a perspective view of the latch viewed from the other side thereof.

Fig. 3 is a plan view of the latch.

The dotted line disclosure of fragmentary portions of the door is for illustrative purposes only.

I claim:

The ornamental design for a latch, as shown and described.

CHESTER O. GOSERUD.
